CLAIM

The ornamental design for an inflatable sprinkler pool, as shown and described.

DESCRIPTION

FIG. 1 is a perspective view of an inflatable sprinkler pool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of of portion 9 shown in FIG. 1; and,

FIG. 10 is an enlarged view of of portion 10 shown in FIG. 3.

The broken lines in the drawings depict portions of the inflatable sprinkler pool that form no part of the claimed design.

1 Claim, 10 Drawing Sheets
